METHOD OF REVERSE PLATING

Elmer U. Ames, Collingswood, N. J.; Agnes A. Seaman, administratrix of the estate of Elmer U. Ames, deceased, assignor to H. Brinton Company, Philadelphia, Pa., a corporation of Pennsylvania

Application May 13, 1925, Serial No. 30,102

7 Claims. (Cl. 66—36)

My said invention relates to a method of reverse plating and it is an object thereof to provide a simple and effective method by which the relative positions of different yarns in a fabric may be reversed with ease and certainty to produce patterns in the fabric.

It has been found that if a machine is set up with regular needles and is adjusted for making plated work, i. e. knitting with two yarns of different color, weight or material and causing one yarn to appear on the inside of the fabric and the other on the outside, and if then certain needles are replaced by others having their hooks set forward or outward from the series by a space, e. g. $\frac{1}{2}$ " or $\frac{1}{8}$ ", all other conditions being the same, then the needles having the regular hooks will throw one yarn on the outside and those having their hooks set forward will throw the other yarn to the outside, making a fabric with vertical plated stripes. A machine may be set up for plating by using separate guides for the two yarns or a single guide with two holes in it, the guide for the face yarn in any case being nearer the cylinder than the other yarn. Usually more tension is also required on the face yarn. When forward and backward sets of hooks are used the forward hooks will plate regularly and the backward hooks will plate reversely.

I have found that by using uniform needles and projecting the hooks of certain needles forward on one round and others in succeeding rounds, all in predetermined order, patterns may be plated on the fabric such as checks, stripes and figures of various kinds.

Referring to the accompanying drawings which are made a part hereof and on which similar reference characters indicate similar parts,

Figure 1 shows a series of needles in elevation in the positions assumed in relation to a pair of yarns while passing a stitch cam,

Figure 2 is a plan view with the upper ends of the needles omitted for the sake of clearness,

Figure 3, a similar view showing the fabric in process of formation,

Figure 4, an elevation also showing the verge of the forming fabric, the needles in Figs. 1, 2, 3 and 4 all being in process of passing the stitch cam,

Figure 5, a view similar to Fig. 2, and

Figure 6, a view similar to Fig. 1 except that the needles have moved a little further with reference to the cam.

In the drawings a pair of yarn guides C and D are indicated as being formed on a single yarn finger E or other guiding instrumentality, the

guide C being nearer the cylinder than guide D. A pair of yarns are shown as passing through guides C and D and said yarns are marked for convenience R and W, the first being hereinafter described as a red yarn and the second as a white yarn. It is of course understood that the yarns may differ by other characteristics without affecting the invention.

As a matter of further convenience tending to correct understanding of the invention the 10 needles are numbered from 1 to 9 and are indicated as being divided into two series, each series consisting of groups of two needles and the groups being set alternately forward and back by any convenient means. The staggered arrangement 15 will be understood by examination of Figures 2 and 3 and the positions of the needles are further marked on Figure 1 as "needles forward" and "needles back". It will be seen that the series including needles 3, 6, 7 are forward, i. e. assuming the machine to be a circular one they are in some way or another forced radially out from the cylinder as compared with needles 4, 5, 8, 9 which are in their normal position at this time. As clearly indicated in Fig. 1 the red yarn is lower 20 than the white and remains so up to the position of needle 7 which being "forward" has the red yarn at the back whereby it will appear on the face of the fabric. Needle 8, however, which has just knocked-over or cast-off its loop, this needle 25 being at its lowest point where it has drawn the new loop to its full extent, has the red yarn at the front whereby it will appear at the "wrong side" or back of the fabric and so has needle 9 which has passed the lowest point of the stitch 30 cam. The different positions of the yarn are further shown in Figures 2, 3 and 4.

Preferably the red yarn has tension on it, this tension being supplied by a pair of tension washers or other convenient tension device and the 40 reverse plating action may be at least partly explained by the fact that this tension tends to draw the red yarn to the top of the hooks at all times while the looser white yarn must find a place as near to the top of the hook as possible 45 due to the pull of the needles and the fact that the new stitches are being drawn down through the old loop. If the hook is forward the yarn with the tension on it (the red yarn in this case) will be drawn to the front of the hook as the 50 needle approaches its lowest position and the other yarn will find a place back of it. The yarns will, of course, remain in the same relative position as the stitches are drawn through the old loops, the yarn that is at the front of the hook 55

showing on the back of the fabric and the other on the face of the fabric. Briefly stated the yarn with greater tension goes to the outside or face of the fabric when knit with forward hooks 5 and to the inside or back of the fabric when knit with backward or set-back hooks.

In Figures 5 and 6 the series of needles has moved forward with reference to the stitch cam to such an extent that the forward needle 6 is at 10 its lowest point of movement (knocking-over point) while needle 7 has passed the low point of the cam. As the forward needles reach the positions indicated in these figures, the red yarn assumes the rear position and the white is at the 15 front, i. e. the red yarn will appear at the face of the fabric and the white at the back.

It will be understood from the foregoing that with the needles arranged and manipulated as indicated in the drawings alternate vertical 20 stripes of red and white will appear on the face of the fabric, assuming that the needles marked "needles forward" are always projected while those marked "needles back" are always in their regular position. By manipulating the needles 25 in ways that will be clear to those skilled in the art, as by means of a jacquard or other pattern mechanism, these stripes may be alternated, or form checks or other figures and many changes in the design of the fabric may be made either by 30 varying the manipulation of the needles or by changing the yarns, etc.

Having thus fully described my said invention, what I claim as new and desire to secure by Letters Patent, is:

35. 1. The method of knitting a reversely plated fabric upon a row of independently movable needles or like instrumentalities by feeding to such instrumentalities a pair of yarns in plating relation, deflecting certain of such instrumentalities laterally out of the row during the knitting of a course of stitches, and moving them toward knocking-over position while so deflected, substantially as set forth.

45. 2. The method of knitting a reversely plated fabric upon a row of independently movable needles or like instrumentalities by feeding to such instrumentalities a pair of differently-tensioned yarns in plating relation, deflecting certain of such instrumentalities laterally out of the 50 row during the knitting operation, and moving them toward knocking-over position while so deflected, substantially as set forth.

3. The method of knitting a reversely plated patterned fabric upon a row of independently movable needles or like instrumentalities by feeding to such instrumentalities a pair of yarns in plating relation, deflecting different instrumentalities of the row in different courses laterally out of the row during the knitting operation, and moving them toward knocking-over position while so deflected, substantially as set forth. 5

4. The method of knitting a reversely plated patterned fabric upon a row of independently movable needles or like instrumentalities by feeding to such instrumentalities a pair of differently-tensioned yarns in plating relation, deflecting different instrumentalities of the row in different courses laterally out of the row while the knitting is going on, and moving them toward knocking-over position while so deflected, substantially as set forth. 10

5. The method of knitting a reversely plated fabric upon a series of independently movable parallel needles or like instrumentalities in a circular knitting machine by feeding to such instrumentalities a pair of yarns in plating relation, deflecting certain of such instrumentalities radially out of the series during the knitting operation, moving them toward knocking-over position while so deflected, and permitting them to return thereafter to normal position in the needle row, substantially as set forth. 20

6. The method of knitting a reversely plated patterned fabric upon a circular series of independently movable needles or like instrumentalities by feeding to such instrumentalities a pair of differently-tensioned yarns in plating relation, deflecting different instrumentalities of the series in different courses radially out of the series during the knitting operation, and moving them toward knocking-over position while so deflected, substantially as set forth. 30

7. That process of effecting a change from normal plating to reverse plating in fabric formed upon a circular series of independent needles comprising operating a circular series of needles independently, and during the knitting operation 45 while two threads are being acted upon thereby in a plating relation, deflecting certain of said needles at the thread receiving end whereby a change from normal plating to reverse plating is effected. 40
